Fig. 3.

1. A water-heating system for a stand boiler, comprising a boiler having a water connection at the top and a hot water take-off connection at the bottom, a coiled pipe means having a lower end terminating in spaced relation above the bottom of the water in the boiler and an upper end terminating in spaced relation above the top of the water in the boiler, the coiled pipe means being connected to the water connection of the boiler, the hot water take-off connection being connected to the coiled pipe means, the coiled pipe means being connected to a water main, the coiled pipe means being connected to a heating coil, the heating coil being connected to a tap.

UNITED STATES PATENT OFFICE

2,598,860

WATER-HEATING SYSTEM

Robert W. Tiley, Ashland, Pa.

Application September 2, 1949, Serial No. 113,699

2 Claims. (Cl. 257—229)

1

The present invention relates to certain new and useful improvements in ways and means whereby cold water, direct from a city main, is delivered to a so-called stand boiler and heated and made ready for tap water or for other domestic consumption purposes in the home and elsewhere.

More specifically, the invention has to do with novel adapter-equipped pipe means which is adapted to be installed in a stand boiler at the time the latter is manufactured and made ready for use, said pipe means embodying a water circulating and heating coil and having ways and means at its opposite ends whereby one end may be joined up with the cold water supply connection and the other end joined up with the hot water take-off or supply connection, the first-named end embodying a novel adapter which comes in handy for expansion and contraction association with heating water which is contained in the stand boiler itself.

It is a matter of common knowledge that the ordinary stand type storage and heating boiler in use today accumulates large quantities of sediment in the bottom thereof which is brought in with the regular water supply; that, in addition, scale accumulates on the interior sides of the boiler with the result that, at times of extraordinary heat, the sediment and silt as well as the scale are severely disturbed and roiled up, with the consequence that the domestic supply of water is frequently and unagreeably clouded and muddied. The ordinary boiler herein under consideration is a type shown, for example, in a patent to one John Neukam 1,775,208 of September 9, 1930, wherein it will be seen that the usual cold water pipe enters the top of the boiler and has its lower end terminating in spaced relation above the bottom of the water and that the hot water take-off pipe is connected to the dome or top of the boiler, various ways and means being employed for heating the water which is delivered into and circulated through the boiler to the hot water take-off pipe.

One object of the invention is to remedy the stated situation regardless of the amount of silt, mud or scale accumulation within the boiler and regardless of the intensity of the heat applied to the water within the boiler, the usable tap water passing through a circulating and heating coil

2

and onto the take-off connection and remaining as clear and drinkable as cold water coming direct from a water main to a tap.

Another object of the invention has to do with the heating of water for domestic consumption by passing the same through special pipe means which is embodied in the boiler and which incorporates a heating coil, thus bypassing the cold water from the cold water connection to the hot water take-off connection while at the same time sending it through the coil and subjecting the coil to heating by other water in the boiler, the tap water not being permitted to intermingle or mix with the heating water in the boiler.

Another object of the invention is to employ the stated construction to the end that the water contained in the boiler and supplying the heat to the water which passes through the coil means remains practically constant and intact at all times so that no appreciable amount of the same at any time finds its way into the coil means and thereafter through the outlet for domestic consumption.

More specifically, the invention has to do with the stated construction wherein the water passing through the coil for domestic consumption is entirely independent of and never mixes with the water in the boiler supplying the heat with the exception of the aforementioned unappreciable amount which is forced, through expansion from the boiler, into the coil means in a manner to be hereinafter set forth.

Then, too, the invention has to do with the stated association of a simple coiled pipe construction with the cold water and hot water connections in a standard type storage boiler wherein the water (1) in the boiler with very slight exception remains constant and not dissipated, its function being to merely furnish heat for (2) the usable water passing through the coiled pipe means and wherein, upon cooling and contraction, the pressure in the stand boiler decreases and the water main pressure automatically serves to force water back through ports in the stated pipe means for initially filling the boiler and thereafter replenishing the supply automatically.

These and ancillary objects and structural features of merit are attained by this invention, the preferred embodiment of which is set forth in

the following description and illustrated in the accompanying drawing, wherein:

Figure 1 is a vertical sectional view, illustrating the interior assembly;

Figure 2 is an enlarged vertical sectional view of a fragmentary portion of the interior assembly, illustrating the expansion adapter, constructed in accordance with the principles of this invention; and

Figure 3 is a transverse sectional view taken on line 3—3 of Figure 2.

Referring now more particularly to the drawings, a tank or boiler 10 is illustrated and is formed with a convex upper end 12 formed with a pair of internally threaded openings 14 and 16.

Inlet and outlet pipes 18 and 20, which are vertically spaced, extend laterally to the side wall of the tank and a drain valve 22 is provided at the lower end of the tank. An air vent 24 is provided at the top 12 of the tank and is installed between the openings, the air vent being provided so that the tank may be completely filled with water.

A cold water supply conduit or pipe 26 is provided with a conventional pressure relief valve structure 28, which is installed in the pipe, the pipe being threaded into an elbow connection 30 which is formed adjacent its opposing end with an annular flange 32. The opposing end is externally threaded, as at 34, and is secured within the opening 16, the flange abutting against the protruding wall of the opening but seating thereon, as seen in Figure 2, to provide a tight connection. The inserted end of the elbow connector is internally threaded to receive the threaded end 36 of a nipple 38. The nipple 38 depends from the inserted end of the elbow connector and extends downwardly in the tank.

A hot water outlet pipe 40 is secured by an elbow connector 42 through the opening 14, a coil 44 being connected at its upper end through the opening 14 and being disposed vertically within the tank. The coil passes into a vertical pipe 46 which is formed with an axially enlarged upper end 48, the enlarged end 48 being concentrically disposed about the lower end of the nipple 38 and being formed with an inwardly tapering upper end 50, which is suitably secured to the nipple below the enlarged section 52 thereof. The enlarged end 48 of the pipe is formed at its adjacent upper end 50 with radially disposed, circumferentially spaced openings 54.

In use, heated water is disposed within the tank on the outside of the coil 44 and the pipe 46, the water being carried to the tank or boiler by the inlet pipe and being heated by any suitable means. The water in the pipe and coil, the pipe 26 being directly connected to the water main, is heated on passing through the coil. The boiler accumulates large quantities of sediment on the bottom thereof and scale formations occur on the sides of the boiler. At times, due to a high temperature of the water, the scale and sediment deposits are agitated and stirred up. But the purpose of this invention is to prevent the water within the boiler, having scale accumulations therein, from passing through the coil and to the outlets and yet to allow the water to expand and contract. Thus, as the water in the boiler expands, it flows through the apertures in the end 48, but the amount of water that will actually enter the tubing or coil, even at high temperatures, will be slight and will not affect the condition of the water supply. Upon contraction of the boiler water, the pressure of the

water in the water main will force fresh water through the openings in the end 48 into the boiler.

The only purpose of the air vent located on the top of the boiler 24 is to facilitate the initial filling; it has no other function. The pressure relief valve 28 is conventional and is merely installed for cases of exceptional pressure in such emergency that the back pressure from the water main might be such to cause destruction. These features are conventional and the inventor claims no art so far as they are concerned.

As above stated, water in the boiler is to remain constant and unchanged with the exception of that slight amount which might be expelled through expansion, this being accommodated by the apertures at the top of the coil 48 and hence in a downward direction to the bottom and passing out through the coil along with the water for domestic consumption. Specifically, note that the water passing through the coil for domestic consumption is entirely independent of and never mixes with the water in the boiler supplying the heat with the exception of the aforesaid unappreciable amount which is forced through expansion from the boiler into the tubing through apertures 34 as aforesaid. It follows then that (A) the water in the boiler, with this very slight exception, remains constant and not dissipated, its function being to merely furnish the heat for (B) the usable water passing through the coil means. Upon cooling and contraction, the pressure in the stand boiler decreases and the water main pressure will automatically force water back through the same apertures keeping the boiler filled at all times.

Having described the invention, what is claimed as new is:

1. In a structure for handling, storing and heating tap water which is free from rust and sedimentation deposits and substantially as pure and uncolored as if delivered directly from a supply main comprising, in combination, a stand tank having a cold water supply pipe connection at its top, a hot tap water delivery pipe connection also at its top, and pipe means being confined in said boiler and communicatively connected at one end with said cold water pipe connection and connected at its opposite end with said hot water pipe connection and provided intermediate its ends with heating coil means, said pipe means conducting the incoming cold water directly to said latter pipe connection by way of said coil means, whereby to prevent said water from intermingling with other water in said boiler which is used solely for heating said coil means, thus eliminating rust, scale or dirt from getting into the consumable heated tap water, said pipe embodying an expansion adapter nipple attached directly to said cold water pipe connection and a concentrically surrounding pipe enlargement, the latter having a plurality of ports, whereby any small amount of water necessarily expelled from the boiler, by expansion from heat, will flow through such openings and pass through the coil and coil outlet along with the water from the main inlet to the consumption taps, and upon contraction of the boiler water the pressure of the water in the cold water main will cause fresh water to flow through said ports, automatically replenishing the boiler.
2. For use in a stand type boiler which includes a water containing and storing tank for heating water and which has a domical top, a cold water supply pipe connection mounted in

said top and a hot water pipe take-off connection also mounted in said top, and wherein said connections are internally screw threaded, means for circulating water directly from one connection to the other comprising an adapter nipple adapted to be screwed into the cold water connection and to depend therefrom into the boiler, a second adapter nipple adapted to be screwed into the remaining hot water connection and to depend into the boiler in spaced parallelism to the first-named adapter, pipe means having one end portion coiled and connected with the second-named adapter and having the opposite end portion linearly straight and terminating in a ported enlargement, the first-named adapter nipple being

adapted to extend concentrically and in spaced relation into said ported enlargement.
